UNITED STATES PATENT OFFICE.

JOSEPH J. SHIPLEY, OF WASHINGTON, DISTRICT OF COLUMBIA.

AUTOMATIC HEADLIGHT-DEFLECTING MECHANISM.

No. 902,117.

Specification of Letters Patent.

Patented Oct. 27, 1908.

Application filed May 17, 1906. Serial No. 317,370.

To all whom it may concern:

Be it known that I, JOSEPH J. SHIPLEY, citizen of the United States, residing at Washington, in the District of Columbia, have invented certain new and useful Improvements in Automatic Headlight-Deflecting Mechanisms, of which the following is a specification.

The invention relates to headlights or lamps for motor-vehicles, such as automobiles and autocars; and it consists essentially of the novel construction and arrangement of mechanisms, whereby a plurality of headlights or lamps may be rotated in unison to project the light along the line of travel of the vehicle, whether the direction of travel be in a straight or curved course.

The invention further consists of means for connecting the headlights or lamps in such a manner, that motion imparted to either one will be transmitted to the other, so that both headlights or lamps will be caused to move synchronously.

The invention still further consists of means for effectively absorbing the occurring variations in the connections between the headlights or lamps and the steering-knuckles or stub-axles, which variations are due to the jolting or jarring motion of the vehicle body, when the vehicle passes over obstructions or uneven places in the roadway.

One of the principal objects of the invention is to provide a simple and inexpensive mechanism for operating the headlights or lamps of automobiles, autocars, or similar motor-vehicles, so as to cause their light to be reflected in the direction of travel of the vehicle in turning corners or rounding curves.

Other objects of the invention will become readily apparent upon a full disclosure thereof.

In the drawing, Figure 1 is a perspective view of the forward or front portion of a motor-vehicle of the ordinary type, equipped with my improved mechanism for operating the lamps; Fig. 2, a side elevation of one of the lamp-supports and brackets, partly in section to show the ball-bearings; Fig. 3, an enlarged top plan view of one of the clamp-arms that is secured to the steering-knuckle or stub-axle; and Fig. 4 a similar view, showing the clamp-arm secured to one of the steering-knuckles.

In the several views, the numerals 1, 1 in 55 indicate the steering-knuckles of the front axle, 2, and 3 the body of the car. The body is

supported upon springs in the usual manner, the front end of the body being provided with the usual forwardly-projecting bearers or arms 4, 4, to which the ends of the front springs are attached, and as thus supported the body will have a limited vertical movement whenever the car passes over obstructions or uneven places in the roadway, which movement is due to the resiliency of the 65 springs.

The present invention being applicable to any type of motor-vehicle, it is not deemed necessary, for a complete understanding of the invention, to describe or refer to any part or parts of the car other than the steering-knuckles, body-bearers or arms, and springs as these are the only members or elements which coöperate with my improved mechanism for operating the lamps, two of which are 75 usually employed on all motor-vehicles.

Secured to the car-body, at each side thereof, is a bracket 10, which is provided with a vertical sleeve 9 having at each end a ball-race 11. Journaled in each sleeve is a 80 lamp-support 12 having a forked head 13 in which the lamp is mounted, as shown in Fig. 1. Each lamp-support is provided with a fixed cone-bearing 14 and an adjustable cone-bearing 15, and balls 18 are placed in 85 the races, at the respective ends of the sleeve, to provide upper and lower ball-bearings for the lamp-support, the cone-bearing 15 being held in adjusted position by means of a jam-nut 16.

Secured to each lamp-support is a bell-crank lever 17, and the two supports are connected by means of a suitable connection 19, pivotally-attached to one arm of each of the bell-crank levers. As thus connected, both 95 supports, and thereby the lamps, will be caused to rotate in unison when motion is transmitted to either.

Attached to the T-shape tenon 8 of each steering-knuckle is a clamp-arm 6, which is 100 set at an angle corresponding to that of the outer arm of the bell-crank lever, to which it is attached or connected by an elastic or resilient connection. This elastic or resilient connection, in the present instance, consists 105 of a rod or wire 19', having one of its ends pivotally-connected to said arm of the bell-crank lever, and its other end, which is slightly bent, connected to the clamp-arm 6, each clamp-arm being provided with a rectangular opening or slot 7, arranged at a right-angle to the steering-knuckle, as shown in Fig. 110.

4, in which slot the bent end of the rod or wire is yieldingly held by a compressible spring 20 fitted in said slot. When under the influence of a jolt or jar, the ends of the rods or wires are forced against the tension of the springs 20 and instantly returned to normal position. Thus it will be seen that the variations of the distance between the clamp-arms and the car-body, which variations are due to the jolts or jars, are effectively counteracted and the straining of the parts prevented.

It will be evident that other well-known means for absorbing the occurring variations in the length of the connections between the lamps and the steering-knuckles may be employed, so long as such means render the connections elastic or resilient, and therefore I do not wish to be understood as limiting my invention to the employment of springs for such purpose. It will also be evident that the connection between the lamps may be made in any suitable manner, so long as it will operate to transmit motion imparted to either of said lamps to the other.

Having thus fully described my invention what I claim, is—

1. In a motor-vehicle, a spring-supported body, steering-knuckles, duplicate lamps rotatably-supported from said body, a connection between the lamps whereby they may be moved in unison, means connecting one of the steering-knuckles with one of the lamps, and means connecting the other steering-knuckle with the other lamp, whereby both of said lamps may be rotated to project the light in the path of travel of the vehicle when turning corners or rounding curves.

2. In a motor-vehicle, a spring-supported body, steering-mechanism, duplicate lamps rotatably-supported from said body, mechanism connecting said lamps, and elastic or resilient connecting-mechanism arranged to transmit motion from the steering-mechanism to each of said lamps, whereby they will be caused to move in unison and project the light in the path of travel when the vehicle is turning corners or rounding curves.

3. In a motor-vehicle, a spring-supported body, steering-knuckles, duplicate lamps mounted in suitable supports journaled in bearings attached to said body, means connecting the lamps so they may be moved in unison, and connecting mechanism arranged to transmit motion from the steering-knuckles to each lamp-support, whereby both supports will be caused to rotate in unison and project the light in the path of travel when the vehicle is turning corners or rounding curves.

4. In a motor-vehicle, a spring-supported body, steering-knuckles, duplicate lamps mounted in supports journaled in suitable bearings attached to said body, means connecting the lamp-supports so that motion

transmitted to either one will be imparted to the other simultaneously, and elastic or resilient connections arranged to transmit motion from the steering-knuckles to the lamp-supports, and thereby cause both supports to rotate and project the light in front of the car.

5. In an automobile, a spring-supported body, duplicate lamps supported from said body and partaking of the movements permitted by the supporting springs, said lamps being movable about a vertical axis, steering-mechanism for said automobile, connecting-mechanism including a resilient member adapted to transmit motion from said steering-mechanism to each of said lamps, and other means connecting said lamps and acting to transmit motion imparted to either one of said lamps to the other.

6. In an automobile, a spring-supported body, brackets supported so as to partake of the movements permitted by the supporting springs, a vertical rod rotatably carried by each of said brackets and adapted to support a lamp, a bell-crank lever carried by each of said vertical rods, stub-axes for the front wheels of the automobile, an arm carried by each of said stub-axes, a resilient connection between each of the arms of said stub-axes and one of the arms of said bell-crank levers, and a member connecting the other arms of said bell-crank levers.

7. In a motor-vehicle, a spring-supported body, steering-knuckles, slotted arms attached to the steering-knuckles, lamp-supports rotatably-mounted from said body, wire connections between the slotted arms and the lamp-supports, and means arranged within the slots of the arms for yieldingly holding the ends of the wire therein.

8. In a motor-vehicle, a spring-supported body, steering-knuckles, a slotted arm attached to each steering-knuckle, a lamp-support rotatably-mounted from said body, an arm projecting at right-angles from each lamp-support, a wire-connection between each lamp-support arm and each steering-knuckle arm, and a compressible spring arranged within the slot of each steering-knuckle arm, whereby the end of the wire located in said slot is caused to impinge against the end of the slot and be returned to normal position.

9. In a motor-vehicle, a spring-supported body, steering-knuckles, an arm attached to each steering-knuckle and provided with an elongated slot, a lamp-support arranged in proximity to each arm, a connection between the lamp-supports, an arm projecting from each lamp-support, a connection between each said arm and each steering-knuckle arm, and means arranged within each slot for absorbing occurring variations between the arm of each steering-knuckle and each lamp-support.

10. In a motor-vehicle, a spring-supported body, steering-knuckles, an arm attached to each steering-knuckle and having arranged therein a slot at right-angles to said steering-knuckle, a lamp-support mounted upon ball-bearings in proximity to each steering-knuckle, a connection between each lamp-support, connections between the steering-knuckle arms and the lamp-supports, and 15 means arranged within the slots for absorbing the occurring variations between the arms of the steering-knuckles and the lamp-supports.

11. In a motor-vehicle, a spring-supported body, steering-knuckles, an arm projecting from each steering-knuckle and provided with a slot arranged at a right-angle to said steering-knuckle, a lamp-support rotatably- 15

mounted in proximity to each steering-knuckle arm, a bell-crank lever carried by each lamp-support, a connection between one set of arms of the bell-crank lever, whereby motion transmitted to one lamp-support will be imparted to the other, a connection between each steering-knuckle arm and the other arm of each bell-crank lever, said arms being set at corresponding angles, and a spring arranged in each slot for holding the end of the wire-connection yieldingly therein.

In testimony whereof I have signed my name to this specification in the presence of two subscribing witnesses.

JOSEPH J. SHIPLEY.
